MACHINE TO FORM PROPELLER BLADES

Edward Skillman, Wichita, Kans.

Application August 13, 1942, Serial No. 454,642

9 Claims. (Cl. 144—144)

My invention relates to a machine to form propeller blades, and has for its principal object to mill from solid timber, plywood, or other material, but hereinafter referred to as timber, propeller blades with a gradual decrease in twist from the hub outward to the tips of the blades, and by turning the propeller on its longitudinal axis, both sides of the blades are formed to coincide with respect to their twist.

A still further object of this invention is to manufacture a propeller with a gradual decreasing twist from the hub outward, and the sides of the propeller may be varied with respect to cross section; in other words, one side being straight in cross section while the other side may be crowned or convexed but the twist maintained along the blades as stated in the principal object.

A further object of this invention is to provide a channel-like structure to receive a timber for a propeller slidable therein longitudinally and power means to slide the propeller longitudinally as milled by a cutter, and the bed being rocked coincident with the sliding movement of the propeller.

A still further object of this invention is to provide a rocking support for each side of the channel, one support being to twist the blade as milled by the cutter, the other support to raise its respective side of the channel to accommodate for cutting step by step, and being subjected to the twisting movement of the first said support.

A still further object of this invention is to provide an automatic means for disengaging the milling process by moving the blade structure from engagement with the cutter, and so retained until manually released for further action.

These and other objects will hereinafter be more fully explained, reference being had to the accompanying drawings, forming a part of this specification, and in which like characters will apply to like parts in the different views.

Referring to the drawings:

Fig. 1 is a rear side elevation of the machine.

Fig. 2 is an enlarged view of one form of cutter as applied to a propeller timber, the latter shown in cross section.

Fig. 3 is a rear side view of the propeller.

Fig. 4 is an edge view of Fig. 3.

Fig. 5 is a front side of the propeller.

Fig. 6 is an enlarged sectional view taken on line 6—6 in Fig. 4.

Fig. 6A is an enlarged end view of the propeller, showing the tip and hub thereof, the lat-

ter being in rectangular form and indicating the size of the timber prior to forming the blade, the dotted lines indicating step cutting of the blade.

Fig. 7 is a front elevation of the machine.

Fig. 8 is an enlarged view of the power control, the valve and cylinder chamber being in section.

Fig. 9 is a left hand end view of the machine.

Fig. 10 is a right hand end view thereof.

Fig. 11 is a sectional view through the beam, adjacent the left hand crank.

Fig. 12 is a top plan view of the machine.

Fig. 13 is an enlarged detail side view of the automatic valve throw for directional control of the piston movement.

Fig. 14 is a transverse view of Fig. 13.

Fig. 15 is a longitudinal sectional view through the timber from which the propeller is formed, said timber being apertured at the predetermined hub and being engaged by a detachable conveyor to move the timber longitudinally.

Fig. 16 is a sectional view taken on line 16—16 in Fig. 1.

Fig. 17 is a sectional view taken on line 17—17 in Fig. 22.

Fig. 18 is an enlarged detail of the control for the upper movement of the bed step by step to its maximum movement.

Fig. 18A is a detail view of the guard pawl at its terminal position to engage the latch.

Fig. 19 is an enlarged view of the turning means for the guard and rockably mounted catch to retain said pawl from engagement with the teeth of the guard, the barrel for the pawl being in section.

Fig. 20 is a sectional view taken on line 20—20 in Fig. 18.

Fig. 21 is a sectional view taken on line 21—21 in Fig. 18.

Fig. 22 represents the assembly of elements to rock the bed upward step by step, the bed in section, and other parts removed for convenience of illustration.

Fig. 23 is a top plan view of Fig. 22, the bed and rocking arm omitted.

Fig. 24 is a modified form from that shown in Fig. 1 to rock the bed through the medium of gear arrangement.

The invention herein disclosed relates to a machine for the manufacture of propellers, the structure of the machine consisting of a pair of leg elements 1 spaced apart and being connected at their upper extremities by a channel-like element 2 with respect to cross section to function as a beam for the support of a super-

structure that consists of a standard 3 vertically disposed and being adjacent each leg of the machine and a centrally disposed standard, said standards being adjustably connected at their respective points of engagement with the beam through the medium of cap screws 4 threadedly engaging in the beam, said cap screws extending through slots 5 in the standards whereby said standards may be vertically adjusted and secured to such position selectively, said standards laterally extending outward from where they leave the upper side of the beam.

The upper end of each standard has a bearing 6 integrally formed thereto to receive a rod 7 rockably therein, each end of the rod being bored diametrically to receive a pin 7' insertible therethrough as securing means for the rod against longitudinal movement, the purpose of said rod later described.

Positioned a spaced distance upward from the beam and being in parallelism therewith is a channel structure to function as a bed in which a propeller timber 8 will engage for longitudinal sliding movement therein and being secured by a rockable spring tensioned clamp 8' rockably secured to the bed adjacent each side of a cutter to bind a blade slidable in the bottom of the bed, said bed consisting of two L-shaped members 9, the horizontally disposed legs of which confront each other with respect to their edges and adapted to be moved toward and from each other to vary the width of the channel, said L-shaped members being connected by cross bars 10, one adjacent each end of the bed and one centrally disposed, said bars having slots 11 longitudinally extending and through which a bolt 11' for each channel leg will extend as adjustable securing means for the L-shaped members as spaced apart and likewise to vary the position of the channel transversely of its length whereby a timber positioned in the channel may be positioned beneath a cutter head, later described.

It will be seen that the said cross bars 10 outwardly extend from the vertical sides of the channel structure to provide ample length to expand the channel with respect to cross section, the ends of the bars extending toward the front of the machine, each being apertured to receive an eye bolt 12, or the like, pendants carried thereby, the bolts being secured by nuts 13 threadedly engaging above and below the bars as locking means for the eye bolts at a predetermined distance downward.

Rigidly secured to rod 7 is an arm 14 for each eye bolt, the free ends of said arms extending toward and being registered with the apertures of said eye bolts for pivotal connection therewith by pins 15 extending through the apertures, said pins being removably secured by pins 16 passing through the first said pins adjacent their respective outer sides of the eye bolts and said arms where they rockably connect, whereby the bed is rocked by a mechanism later described to form the twist of the propeller blades as milled as said blades are moved longitudinally in the bed through the medium of a connecting rod 17 having a head at one end thereof positioned at right angle to the rod so that the head will engage in a centrally disposed bore 18 through the propeller timber. The head has a rockable wedge 19 carried thereby for snug engagement in the bore, the wedge having a spring 20 as separating means therefor from the rigid portion 21 of the head to cause snug engagement, and the convolutions of the spring being compressed to near engagement

5 to avoid longitudinal movement at the time of retracting the propeller for repeated milling by the cutter. The said wedge has a handle A laterally extending from its pivot point connection to loosen the head by an upward lift of the handle at the time of removing said head from the aperture when the propeller is finished or when it is desired to reverse the same end for end to mill in like manner the oppositely disposed blade of the propeller, it being understood that the bore is for hub connection of the propeller to a journaled shaft therefor, the latter not being shown in the drawings.

15 The cutting element or head 22 heretofore referred to is positioned within a casing 23 to function as a guard against accident disaster resulting from flying debris and to guard against personal contact with the cutter. It will be understood that the cutter head is suitably journaled in bearings 24 that are integral with their respective arms 25 at their upper extremities, and likewise an electric motor 26 to turn the cutter, said arm being bifurcated at its lower portion, the legs of which are adjustably secured to its respective side of the beam as shown in Fig. 1, and the motor being actuated from a source of electric energy and having a suitable switch to make and break the current, conveniently positioned to an operator but not shown in the drawings. It will be seen 20 that the vertical legs of the channel are removed arcuately adjacent the cutter as at B to clear the cutter blades.

25 It will be seen that the other side of the bed opposite to that above described is likewise rockably carried by a link, the upper end of which is pivotally connected to a plate 27 that extends across the under side of the bed to reinforce the same where the vertical leg portions of the bed are removed as heretofore stated, said plate being adjustably connected to the bed to function in like manner to that of the said cross bars 10 that likewise connect the L-shaped members of the bed adjustably. The link from its pivot connection down consists of a threaded stud 28 that threadedly engages in the crotch of a yoke 29 for vertical adjustment, the legs of the yoke being adapted to straddle a sleeve 30 and being pivotally connected thereto so that the said sleeve may rock with a lever 31 that diagonally extends 30 across the rear of the beam as shown in Fig. 1, said lever being pivotally connected to the upper end of a cylindrical standard 32, the lower portion of which is threaded to engage in the threaded bearing 33 that is adjustably secured to the side of said beam by bolts 34 engaging in slots 35 extending horizontally through the side of the beam, the standard being so arranged and connected as is adapted for vertical and horizontal adjustment for the lever action.

35 Slidably mounted in close proximity to the upper extremity of the beam is a bar 36 secured by a guide 37 at each end of the machine by bolts 38 engaging through the outwardly extending legs of the guides. The right hand end portion of the bar upwardly extends at right angle and has adjustably secured thereto an extension bar 39 the upper end of which is apertured to receive the connection rod 17 adjustably therein, the rod having on its outer end a nut 40 to threadedly engage on the rod where it extends through the aperture of the extension and a suitable distance each way therefrom. Between the nut and the outer side of the extension bar is a nipple 41 slidable on the connecting rod 17, the end of said nipple where it contacts the nut being straight

while the other end is pointed for rocking movement when the connecting rod 17 is being detached from the propeller by raising the rod at its head, the bore through the extension bar 39 being greater in size than the diameter of the rod to permit rocking movement thereof. Positioned on the other side of the extension bar 39 is a coil spring 42 wound on the connecting rod 17 and secured to abutting engagement with the extension bar 39 by a pin 43 engaging in one of a plurality of apertures 44 diametrically crossing the rod whereby retraction of the propeller timber during its course of formation is moved without sudden thrust as the spring will function as a cushion. The other end of the connecting rod has a head heretofore described as conveying means for the propeller slidably longitudinally of the channel as supporting means therefor during the time of milling the blades.

To actuate the sliding movement of the said bar 36 and its connecting rod 17 to slidably move the propeller is through the medium of an elongated cylinder 45 in parallelism with the bar and on the same plane with respect to their longitudinal axes, said cylinder having pipes 46 and 47 connected with their respective ends of the cylinder to inject and eject alternately to drive a piston 48 positioned in the cylinder, the piston having a rod 49 connected thereto and axially extending through one of the heads 50 of the cylinder. The outer end of the piston rod 49 has a right angle bent portion 51, the end of said portion removably connected to a nipple structure 52 that is secured to the inner side of bar 36 as sliding means therefor reciprocatingly. The said pipes 46 and 47 are connected with a two-way valve consisting of a shell 53 having a core 54 axially extending through the shell whereby an annular by-pass 55 is formed and having connected thereto a feed pipe 56 to connect the same to a source of compression and an exhaust pipe 57. The power element may be water, air, steam, or oil, in case of the latter to preserve the oil a force pump may be employed to return the oil to its source of supply, the pump and supply source not shown in the drawings.

The valve structure is supported by a standard 58 that is connected to the beam, and it will be seen in Fig. 8 that the core 54 of the valve structure has a pair of stop elements 59 oppositely positioned diametrically, each stop adapted to cross the annular by-pass chamber to direct the flow selectively when moved clockwise as shown in Fig. 8, the force of power being transmitted to the left hand end of the cylinder to drive the piston toward the other end and at its terminal movement a means later described will turn the valve anticlockwise to close off the port 46' of the first said pipe and simultaneously open port 47' for injection through its respective pipe into its respective end of the cylinder to retract the movement of the piston and so on reciprocatingly. It will be understood that the said ports 46' and 47' each will function as an exhaust alternately, one of which is illustrated by the closing off of port 47' which in turn will permit the power to exhaust from the cylinder through pipe 47, and vice versa when the valve is rocked.

Inasmuch as ample quantity of power is provided to actuate the machine it will be seen that the retraction of the piston requires a lesser amount of the power inflation due to the head area being reduced by the presence of the piston rod 49, therefore under the same force of impact, retraction of the piston moves with a greater

speed which is desirable to speed up action in the course of milling the propeller whereby time and expense is economized.

To rock the valve there is provided a shaft 60 journalled in the beam adjacent each end thereof, each shaft having a downwardly extending crank 61 secured thereto, said cranks at their lower extremities being connected by a rod 62 for simultaneous rocking of the shafts. Secured to the other end of each shaft is a detent 63 obliquely extending upward and adapted to rock through an arc of approximately ninety degrees reciprocatingly, and seating on their respective stop elements 64 and 65 to avoid excess rocking movement of the shafts, and the said detents being alternately rocked by their respective strikers 66 and 67 that are secured to and carried by said bar 36, the reciprocating movement of the bar being actuated by the piston rod movement heretofore described, which in turn will actuate the valve turning mechanism as illustrated in Figs. 13 and 14.

The valve turning mechanism consists of an arm 68 secured to the core and extending downward to where it integrally joins a sector 69 having a groove 70 in parallelism with the arc of the sector positioned in working relation with a kick spring element and being pivotally connected by a pin 71 to a collar 72 slidably mounted on a square stem 73, said collar being retained by a pin 74 passing through the stem, first said pin 71 to move in the arc of the slot of the sector when the said kick spring element is rocked in either direction past a vertical axis, at which instant the stem will reverse its position as retained by the slotted sector moving from end to end thereof as the bar 36 reciprocates.

It will be seen that spring 75 is wound on the stem 73 and compressed by the collar in the stem's rocking movement from end to end of said slot. The expansion of the spring will suddenly rock the valve core through the medium of its arm 68 heretofore described. It will be seen that the stem at its lower extremity is rockably connected on a pin 76 that is secured to a side of the beam, the stem extending downward from its pivot point and having a pin 77 to engage in the opening 78 of a link 79 that is rigidly secured to the connecting rod 62 which in turn rocks the kick-off element from side to side as said connecting rod 62 moves reciprocatingly. To avoid twisting movement of the stem as engaged by the sector there is provided an arm 80 oppositely disposed to the sector and having its free end pivotally connected to the collar while its upper end is rockably connected to the standard 58. Furthermore said arm 80 in its arcuate movement will avoid frictional engagement along the upper side of the arcuate groove in the sector 69.

It will be seen that lever 31 as diagonally extending from its rockable connection will cross said bar 36 and being slidably connected thereto by a sleeve 81 that is rockably connected to the bar whereby when the bar is moved toward the right hand end of the machine, the lever is rocked upward as indicated by dotted lines 82 which in turn will raise the said link to rock its respective side of the propeller retaining bed upward and return the same proportionately as controlled by the sleeve 81 to turn the propeller as milled by the cutter to graduate and accurately form a desired twist for the propeller blade as the bed is rocked upward as stated in the first object.

It will be understood that the cutting steps for the propeller are accomplished by a mechanism

positioned on the front of the machine, the arrangement of which is as follows:

Coacting with the rocking mechanism for the propeller bed above described there is provided a crank 83 on the front end of shaft 60 adjacent the left hand end of the machine, said crank rockably connected to the lower end of a link, the other end of the link being rockably connected to the free end of a pawl carrying lever 84, the other end of the lever being rockably carried on shaft 7 to function as a pivot point for the lever, the link consisting of a longitudinally divided shaft 85, and connected by a turnbuckle 86, threaded in such a way as to expand or contract the shaft longitudinally as an adjustable feature. The upper end of the link has a universal joint connection 87 with the aforesaid pawl carrying lever 84 to rock the same on a vertical plane as turning means for a sector 88 functioning as a guard to restrict the engagement of a pawl 89 in its action upon a toothed sector portion of a circular disc element 90 that is journaled on said shaft 7 to turn the disc step by step, the movement of which is transmitted to the shaft through the medium of a lever 91, the inner end of which is rigidly secured to said shaft and the said lever has a spring actuated pawl 92 on its side to engage with the notches 93 of the sector formed on the periphery of the disc, whereby the shaft may be turned and become subject to the action of pawl 89 to raise said arm 14 step by step which in turn carried the bed for a repeated cutting of the propeller. It will be understood that the rocking movement of the bed will move to its downward maximum position by each downward stroke of the crank 83 and likewise the retraction movement of the pawl 89, the latter being free to move a greater distance downward due to the fixed stroke of crank 83 that actuates the pawl 89 but has no action on the arm 14 in its downward stroke, the arm being free to rest on its stop element 94 that is stationed on the beam so that the upper end of the stop element will engage the knuckle joint of said arm 14 and eye bolt 12 and where it rests until it is picked up by the said pawl 89 acting upon its disc to turn the shaft, and each upward stroke will raise the side of the bed adjacent the eye bolts one step higher each stroke as the pawl engages the teeth of its disc. It will be seen that the teeth engaged by the pawl 89 are restricted in consecutive order as the said pawl slides downward over the guard 88 that is stepped downward by the pawl carrying arm 84 to expose the next succeeding tooth or teeth that is picked up by the pawl 89 to rock the bed one notch higher, the upward rocking movement of the bed being means to move the propeller as carried by the bed toward the power actuated cutter to gradually reduce the timber to a final cut that determines the thickness of the propeller blade and gradually twist the same coacting with the graduated twisting movement provided for on the rear side of the machine heretofore described.

When one side of the propeller has been formed the timber will be turned over to form the other side and for this form I have illustrated in Figs. 6 and 6A a variation in the sides; in other words, the rear side of the propeller blade may be formed as shown in Fig. 6 in which instance a cutter 95 similar to that shown in Fig. 2 is employed. In this instance the cutter will act principally from one edge portion of the blade to crown its respective side with respect to cross section and being subject to the twisting

movement described, whereby a leading edge is formed. It will be seen that the illustration in Fig. 2 represents the final cutting of the blade at its tip for its respective side, the other side as illustrated not being milled. It will be understood that the milled side of the blade shall be furred up as at C to avoid chattering, while the other side is being milled.

In Fig. 22 is illustrated the controlling elements for action of pawl 89 that is rockably carried by its carrying arm 84 and tensioned to engagement by a spring 96 secured to the arm 84 and engaging on the outer side of the pawl 89, the point of the pawl 89 being adapted to engage with the disc heretofore stated. To restrict its engagement with one tooth at a time, there is provided the guard sector 88 consisting of a web having an arcuate flange 97 integral with the arcuate edge of the web, said guard rockably mounted on shaft 7 and frictionally retained by a spring element 98 engaging on the shaft 7 and positioned between the web and a pin 99 extending through the shaft, being so assembled, will avoid easy rocking movement of the guard. The said flange 97 extends outward each way from the sides of the web, one side extending over the toothed portion of the disc and the other side has a series of internal teeth 100 to be acted upon by a pawl 101 that is carried by elongated tube 102 that is rockably mounted on the shaft 7, said pawl 101 slidably engaging in the tube to engage with the internal teeth 100 of the flange and being tensioned outward to engagement therewith by a spring 103 seated in the bottom of the tube, the shaft of the pawl having a notch 104 across one side thereof to be engaged by a rockably mounted catch 105 when the pawl is forced inward sufficiently to engage the catch. The tube has an elongated slot 106 diametrically positioned and extending longitudinally of the tube to engage a pin 107 extending through the pawl 101 to retain the same from turning movement but free to move longitudinally. The said pawl structure is positioned between the first said pawl carrying lever 84 and web of the sector 88 and being rocked by said lever to move the guard in one direction step by step by the reciprocating movement of said arm whereby the teeth on the disc are exposed in consecutive order to be engaged by the first said pawl 89 to raise the propeller bed for consecutive milling step by step from the outer surface of the timber to the finishing cuts for the blade.

The said lever 84 has a pair of oppositely disposed discs 108 eccentrically mounted to vary the space between said discs by turning the same selectively and there being secured by bolts D engaging through their respective ears E that are integrally joined to the lever, the discs being the contact elements to rock the pawl 101, the excess space between the discs being to provide idle movement of the lever to avoid movement of the guard equal to the rock of the crank 83 but rather to engage the teeth consecutively to move the guard, at which time the bed is rocked downward to free the timber for longitudinal movement for a repeated step of milling, at which time the bed is raised, this being accomplished by the upward rock of the crank 83, which in turn moves the pawl along the guard until the tip of the pawl engages a tooth of the disc whereby the bed is retained until the cutter has milled the blade from the hub outward to the tip, and each successive engagement of

the disc teeth by the pawl 89 is means to raise the bed step by step until one side of the blade is finished. At the finishing cut the pawl 101 will have reached a slanting portion 109 at the end of the teeth series that will function as a cam to force said pawl 101 inward sufficiently for the catch 105 to engage in its notch and being so retained the pawl 101 is inactive regardless the action of the crank 83. At the time of permanently disengaging the pawl 101 by its catch when the milling of the blades is finished and upon replacing the timber or changing the same the catch will be tripped by a downwardly extending handle 110 for repeated engagement of the pawl 89 upon the guard for repeated milling of another side.

It will be seen that the pawl rocking means for the guard as heretofore stated determines its movement in contact with the cam, the cam extending inward sufficiently to force the pawl to its engagement with the catch, at which instance the tube engages a spring tensioned lever 111 through the medium of its roller 112 on the free end of the lever to rock the same on its pivot point as at 113, and the lever outward from its pivot point has a rockable spring tensioned pawl 114, the point of which engages with teeth 115 spaced along the side of a latch 116, by which means said latch is moved outward to extend beyond the periphery of the guard to function as a catch for pawl 89 to rock the guard to its extremity, covering the teeth on the disc to disengage the raising means for the bed, during which time a propeller may be turned for further milling or replaced by another timber. The finishing strokes required to smooth the surface of the propeller are accomplished prior to the last said pawl's engagement to rock the guard as above stated. At the time of projecting the latch sufficient to engage the pawl, tongue 116 of the latch will permit the end of the tube as at F to move toward the latch the thickness of its shell, said amount of movement being sufficient to permit the catch engagement to lock the pawl 101 against further action for the purpose heretofore stated.

It will be seen that the latch is frictionally retained against free longitudinal movement by the end of a friction plunger 117 in contact with the side of the latch, the plunger being tensioned by a coil spring 118 wound thereon, and to retract the latch for further action to mill a propeller is accomplished by a lever 119 having a slot longitudinally therealong to engage on a pin 120 to rock the lever manually by a knob 121 positioned on its free end, and being so arranged the lever will slide longitudinally as the latch is retracted to its normally disengaged position. To retract the latch, the pawl 114 is disengaged by a manual downward push on its knob 122 positioned on its free end outward from the pivot point. It will be seen that the latch may be adjustably positioned at a predetermined point to stop the latch through the medium of a detent 123 against which the end of the lever 119 directed theretoward will engage, the detent being rockable on a pin 124 and has a handle G outwardly extending therefrom to rock the detent. Between the point of the detent and its rockable point there is positioned transversely to the shaft of the detent an elongated link 125 having a bolt 126 extending therethrough that is secured to the web of the guard, the bolt having a nut to fasten the detent at a predetermined point to retain the latch at its normal retracted position.

The spring tensioned lever 111 having a roller on one end and a spring tensioned pawl for the latch on the other are retracted to their normal position through the medium of their respective springs 111' and 114'.

Fig. 24 illustrates a modified method to substitute the link connecting the lever 31 with the bed. The said figure illustration provides a gear 127 adjustably secured to said lever, its teeth being in mesh with the teeth of another gear 128, the upper end of the latter being connected to the bed similar to that of the link. Inasmuch as the link was provided for longitudinal adjustment, the gear 127 is likewise adjusted for such equalization by an arcuate slot 129 through the gear to receive a bolt 130 as securing means for the gear to the lever.

It is also anticipated in this invention that single propeller blades may be manufactured with the same efficiency as the blades herein disclosed, such blades individually to be secured to a suitable hub at the discretion of the manufacturer skilled in the art of such production, and further the electric motor may be substituted by pulleys or other power transmitting elements, and such other modifications may be made as lie within the scope of the appended claims.

Having fully described my invention what I claim as new and desire to secure by Letters Patent is:

1. In a machine to form propeller blades, a beam of suitable length and legs to carry the beam horizontally, and a channel of suitable length and being supported in parallelism with the beam by a pair of means, each of which is rockably connected to its respective side of the channel and adapted to coact while a timber positioned in the channel is being formed into a propeller, and means to slidably move the timber longitudinally in the channel while said channel is being rocked, a cutter and power means to actuate the cutter, said cutter being journaled in working relation to the timber and carried by the beam, means to raise one of the said channel carrying means to engage the timber with the cutter, and means to rock the other channel carrying means to form a twist for a blade as milled by the cutter, and power means to actuate the raising and rocking movements of the channel carrying means.

2. In a machine to form propeller blades, a beam and legs to carry the beam, a channel and carrying means to carry each side of the channel a spaced distance upward from the beam, a cylinder carried by the beam in working relation to the channel, the cylinder having a piston therein and a rod carried by the piston, the rod extending outward from one end of the cylinder, a bar slidably carried on the beam adjacent the cylinder, means to connect the piston rod to the bar, a rod having a head on one end thereof, said rod adapted to engage with a timber positioned in the channel as sliding means for the timber, and means to connect the rod to the bar, said headed rod and bar being moved longitudinally by the piston rod reciprocatingly, and power means to energize the cylinder.

3. In a machine to form propeller blades as recited in claim 2, one of said carrying means consisting of a standard vertically carried by the beam, a lever having one of its ends rockably connected to the upper end of the standard and slantingly crossing the beam and said slidable bar, a sleeve rockably carried by said slidable bar and through which the lever will slidably

engage to rock the lever as the said slidable bar is moved longitudinally, a link rockably connecting one side of the bed to the lever adjacent its standard whereby the said side of the bed is rocked vertically, said other carrying means to raise the other side of said bed step by step in coaction with the rocking movement of the first said side to twist a blade as formed from the timber, decreasing the pitch of the twist as it approaches the tip of the blade.

4. In a machine to form propeller blades, a horizontally positioned beam, a bed for a propeller timber placed above the beam and in parallelism therewith, means for each side of the bed to support the same on said beam, a reciprocating actuated bar carried by the beam in parallelism therewith, means to connect the bar to one side supporting means for the bed to raise said side of the bed by the movement of said bar in one direction, and means connected to the bar for the other side supporting means for the bed to move its side gradually upward when the first said side of the bed has been raised, and a power actuated cutter positioned above the timber to form a propeller from said timber, conveying means for the timber to move the same longitudinally beneath the cutter, and means to attach said conveying means to said bar to move said timber.

5. In a machine of the class described to form propeller blades, the machine comprising a beam of suitable length and legs to carry the beam on a horizontal plane, an elongated cylinder carried by the beam at its upper extremity and in parallelism therewith, the cylinder having a piston rod therein, the rod outwardly extending from one end of the cylinder, and power means to energize the piston movement reciprocatingly and carrying the rod therewith, an elongated bar carried by the beam in working relation to the cylinder, a bed positioned upward from the beam and being in parallelism therewith means carried by the bar for moving a propeller blank along said bed, a shaft and standards to carry the shaft in working relation to the bed, arms having one end of each secured to the shaft, and rockable means to connect the other ends of the arms to one side of the bed, means to turn the shaft to rock the arms upward to raise their respective side of the bed step by step, a cutting head and motor journalled on the arm in working relation to the bed, the arm being secured to the beam so that the bed when rocked will move toward and from the cutter head.

6. In a machine to form propeller blades, a beam horizontally positioned, a plurality of standards upwardly extending from said beam, the lower ends of said standards being adjustably secured to said beam, a shaft rockably carried by the upper ends of said standards, a bar slidably carried by the beam, and power means to move the bar reciprocatingly, and a valve mechanism to cause reverse movement of the bar, shaft and crank means therefor to rock the first said shaft when the bar is moved, a propeller carrying bed positioned above the beam, connecting means for one side of the bed to said shaft to rock the bed when the shaft is turned, supporting means for the other side of the bed, means to connect said supporting means to the bar to gradually raise and lower its respective side of the bed, a conveyor to move the timber longitudinally in the bed, and means connecting the conveyor to said timber and bar to move said conveyor, a power actuated cutter

adjustably carried by the beam, said cutter being positioned above the bed to engage the timber as raised theretoward by the rocking movement of the first said shaft.

- 5 7. In a machine to form propeller blades, a beam of suitable length and legs to carry the beam horizontally, a channel-like bed carried in parallelism with the beam and upwardly spaced therefrom, the said channel-like bed
10 adapted to receive a timber therein and means to move the timber longitudinally in the bed, said timber to be milled into a propeller, a shaft journalled in parallelism with the bed, said shaft being carried by standards that are secured to the beam, a plurality of arms having one end of each rigidly secured to the shaft in spaced relation therealong and extending toward the bed, the other ends of said arms being rockably connected to one side of the bed, means to turn
15 the shaft to raise its adjacent side of the bed step by step for repeated milling of the timber to form a propeller blade, a cutter and a motor to turn the cutter, each of which are journalled on an arm that is secured to the beam, said cutter extending over the timber to mill the same as moved longitudinally thereunder repeatedly and the timber being raised by the bed for each successive milling step by step, means rockably connected to the other side of the bed to gradually raise the same to twist the propeller blade
20 gradually from one end thereof to the other as milled by the cutter, the slant of the twist being decreased gradually as it terminates at the said other end which is the tip of the propeller blade.
25 30 35 8. In a machine to form propeller blades, a beam of suitable length and legs to carry the beam horizontally, and a channel of suitable length and being supported in parallelism with the beam by a pair of means, each of which is
40 rockably connected to its respective side of the channel and adapted to coact while an element from which a propeller is formed is positioned in the channel, and means to slidably move the element longitudinally in the channel while said channel is being rocked, a cutter and power means to actuate the cutter, said cutter being journalled in working relation to the element and carried by the beam, means to raise one of the said channel carrying means to engage the
45 50 55 element with the cutter, and another means coacting with last said carrying means to discontinue raising of the channel at a predetermined point, means to rock the other channel carrying means to form a twist for a blade as milled by the cutter, and power means to actuate the raising and rocking movements of the channel carrying means.
60 65 70 75 9. In a machine to form propeller blades, said machine comprising a base, an elongated horizontally positioned bed carried by said base and adapted to receive a piece of material from which to form a propeller blade slidably longitudinally therein, a rotatable cutter carried by the base and adapted to engage the piece of material to mill the same, a horizontally positioned shaft in working relation to one side of the bed, means to support said shaft rockable to said base, connecting means for one side of the bed to said shaft, an elongated reciprocating element carried by the base, a diagonally positioned lever carried in working relation to the other side of the bed, separate means to connect the lever to the reciprocating element and its respective side of the bed, respectively, for gradual raising and lowering of the bed alternately in the element's

rocking movement, means for attaching said piece of material to said element for sliding movement thereof, a feed controlling mechanism mounted on the said shaft to move the shaft side of the bed upward step by step as the piece of material is milled, means connecting the mechanism to said reciprocating element to ac-

tuate said feed controlling mechanism, said mechanism comprising a means to disengage the mechanism from further raising of the bed when the bed has been raised to a predetermined position, all and for the purpose specified.

EDWARD SKILLMAN.
